UNITED STATES PATENT OFFICE.

JESSIE E. M. SEALE, OF ODESSA, FLORIDA.

AEROPLANE.

Application filed July 12, 1923. Serial No. 650,998.

To all whom it may concern:

Be it known that I, JESSIE E. M. SEALE, a citizen of the United States, residing at Odessa, in the county of Pasco and State of Florida, have invented certain new and useful Improvements in Aeroplanes, of which the following is a specification.

This invention relates to certain new and useful improvements in aeroplanes, and has 10 particular reference to the provision of novel and improved means for the propulsion of the same.

An object of the invention is to provide propulsion means for aeroplanes by means 15 of which a large area of open space is not required for proper landing or launching of the aeroplane.

Another object of the invention is to provide means whereby the forward movement 20 of the aeroplane is insured upon ascension of the plane to a predetermined height.

Other objects will appear as the nature of the invention is better understood, and the same consists in the novel form, combination 25 and arrangement of parts hereinafter more fully described, shown in the accompanying drawings, and claimed.

In the drawings forming part of this application, like numerals of reference indicate similar parts in the several views, and wherein:

Figure 1—is a top plan view of an aeroplane, constructed in accordance with the present invention.

Figure 2—is a bottom plan view thereof, partly broken away.

Figure 3—is a longitudinal sectional view of one of the wings taken substantially upon line 3—3 of Figure 1, and

Figure 4—is a fragmentary elevational view showing one of the wings in rear elevation.

Referring more in detail to the drawings, the embodiment of the invention as shown 45 consists of a biplane having a fuselage 5, with wings 6 extending from opposite sides of its forward portion, and provided with a seat 7 at its forward end for reception of the pilot, the tail portion of the fuselage being provided with the usual horizontal rudders 8 and vertical rudders 9 for controlling the course of travel.

In accordance with the present invention, the wings 6 are of hollow construction, as 55 shown in Figure 3, and have their forward

edges formed as at 10 with a stream line effect, so as to offer little resistance, while travelling through the air. These wings are tapered rearwardly to a considerable thickness, so as to present relatively wide flat 60 rear edges 11, whereby considerable displacement of the air is had, the rushing of which in behind the broad rear edges 11 assists in the forward propulsion of the aeroplane. 65

The lower wall of each of the wings is provided with a substantially central opening, in which is fixed the intake end of an angular air tube 12, which extends forwardly toward the front edge of the wing 70 within the latter as shown in Figure 3. Arranged within the intake portion of each of the tubes 12 is a blower fan 13, adapted to be rotated for drawing air into its tube 12 and forcing the same out of the forward 75 end of said tube into the interior of the wing, and against the interior face of the forward portion thereof. The blower fans 13 may be mounted on a common shaft 14, extending transversely of the aeroplane toward and into the fuselage 5 where it is operatively connected to a suitable engine 15. 80

As shown in Figure 4, each of the wings is formed with a relatively large opening in the rear edge 11 thereof, which opening is 85 normally closed by means of a door or gate 16, which may be provided with a closing spring 17.

In operation, the engine 15 is started for driving the shaft 14, and the blower fans 13 are fixed thereon. This causes the air to be forced through the tubes 12 into the interior of each of the wings, and against the forward portion of the same thereby building up an air pressure within the wings. This 90 will result in causing an almost direct ascension of the aeroplane until the pressure built up within the wings exceeds the strength of the closing springs 17. When this takes place, the air pressure within the 100 wings causes the gates 16 to swing outwardly and downwardly to open position, so that the air will rush out of the openings closed by said gates and will thereby cause forward movement of the aeroplane. 105

It is believed that the purpose and operation, as well as the advantages of the present invention will be readily understood and appreciated by those skilled in the art, from the foregoing description.

Minor changes may be made therein, without departing from the spirit and scope of the invention as claimed.

Having thus described my invention, what I claim as new, and desire to secure by Letters Patent, is:

1. In an aeroplane, a fuselage provided with oppositely projecting laterally extending hollow wings formed with openings in their rear edges, spring closed gates normally closing said openings, and means associated with each wing for drawing air upwardly into the same and forcing said air against the interior surface of the forward portions of the wings to build up an air pressure within the wings sufficient to open said gates.

2. In an aeroplane, a fuselage provided with laterally extending wings, said wings being of hollow form with stream line front edges, and relatively wide flat rear edges, said rear edges having openings therein, spring closed gates normally closing said openings, the lower walls of the wings being provided with openings, angular air tubes fixed in said openings and projecting forwardly therefrom in the interior of the

wings, and blower elements positioned in the intake ends of said air tubes for forcing air through the latter against the interior surfaces of the forward portions of the wings and for building a pressure within the wings sufficient to open said gates.

3. In an aeroplane, a fuselage provided with laterally extending wings, said wings being of hollow form with stream line front edges, and relatively wide flat rear edges, said rear edges having openings therein, spring closed gates normally closing said openings, angular air tubes fixed in said openings and projecting forwardly therefrom in the interior of the wings, and blower elements positioned in the intake ends of said air tubes for forcing air through the latter against the interior surfaces of the forward portions of the wings and for building a pressure within the wings sufficient to open said gates.

In testimony whereof I affix my signature.

JESSIE E. M. SEALE.
